US0D1006822S

(12) **United States Design Patent** (10) **Patent No.:** **US D1,006,822 S**
Matthews et al. (45) **Date of Patent:** **** Dec. 5, 2023**

(54) **TOUCHSCREEN DISPLAY BOOM
GRAPHICAL USER INTERFACE**

(71) Applicant: **Rockwell Collins, Inc.**, Cedar Rapids, IA (US)

(72) Inventors: **Cheyenne Matthews**, Marion, IA (US); **Caleb Owenby**, Greenback, TN (US)

(73) Assignee: **Rockwell Collins, Inc.**, Cedar Rapids, IA (US)

(**) Term: **15 Years**

(21) Appl. No.: **29/756,780**

(22) Filed: **Oct. 30, 2020**

(51) LOC (14) Cl. **14-04**

(52) U.S. Cl.

USPC **D14/485**

(58) **Field of Classification Search**

USPC **D14/485-95**
